UNITED STATES PATENT OFFICE.

EDUARD GROSSE, OF WACHWITZ, NEAR DRESDEN, GERMANY.

PRINTING MACHINE.

Application filed May 5, 1921. Serial No. 467,188.

To all whom it may concern:

Be it known that I, EDUARD GROSSE, a subject of Germany, and residing at Wachwitz, near Dresden, Grundstrasse 8, Germany, have invented certain new and useful Improvements in Printing Machines, of which the following is a specification.

The present invention relates to a printing press of the platen type with sheet delivery device and especially with grippers and spreaders guided by means of endless bands, chains or other means of conveyance. The gripping and spreading devices for sheet delivery are arranged in a very simple and natural manner by being connected to the same means of conveyance which cause the movement of the inking rollers. The grippers, spreaders and inking rollers are jointly guided around the middle part of the press by means of endless bands, chains or other means of conveyance; during this movement are the inking rollers supplied with ink from an inking arrangement and ink the form, while the grippers, after the printing process has been carried out, catch the sheet lying on the platen, take it along, turn it and deposit it with the printed side upward on a table arranged above the press. This represents an extremely simple yet very appropriate arrangement which keeps the platen absolutely free and accessible from all sides as in platen presses without delivery device. The form can be put in and taken out without any difficulties.

The invention relates also to a cylinder inking arrangement over whose large cylinder the inking rollers which are guided around the middle part of the press pass in such a manner that the movement of the inking rollers takes place in the opposite direction to the rotary movement of the inking cylinder. By thus arranging an opposite direction of the two movements the travel of the inking rollers is accelerated, as both movements are added and the inking rollers forced to rotate quicker by means of the cylinder which rotates in the opposite direction. The result of this arrangement is an excellent distribution of ink, as the inking rollers pass from 5 to 8 times over the inking cylinder, according to the quicker or slower rotation of the latter.

One form of the invention is illustrated

in the accompanying drawings, in which Figure 1 is a side view of the platen press; Fig. 2, a partial side view on an enlarged scale; Fig. 3, a modified form of the gripper arrangement; Fig. 4, a side view of the platen press in modified form; Fig. 5, a view of the gripper in this form of execution; Fig. 6, a side view of the platen press with partially cut cylinder inking arrangement.

The middle part of the platen press, suspended within the frame 1, is equipped on both sides of its lower and upper portion with the disc or sprocket wheels 2 and 3 (Fig. 1). The sprocket wheel 2 is driven by means of the spur wheels 6, 5 and 4 dimensioned in such a manner that the bands or chains 10 placed around the sprocket wheels 2 and 3 travel once around the body of the press during each to-and-fro movement of the platen 7 (Fig. 6). The platen 7 is moved by means of a crank attached to the spur wheel 6 and connected at 8 to the platen by means of a rod 9. Over the discs or sprocket wheels 2 and 3, arranged on both sides, run endless steel bands or chains 10. To the latter is connected on each side of the press a roller carriage 11 which follows the movement of the steel bands and, during each to-and-fro movement of the platen 7, travels once around the center of the press in the direction of the outer arrow in Fig. 6. On the carriage rest the inking rollers 12, 13 and 14.

The inking rollers 12, 13 and 14 rotate over the surface of the ink cylinder 19 and receive from the latter the ink which has been transmitted to the cylinder 19 from the duct 22 by means of the roller 20 and the distributing rollers 21. The process of receiving ink from the ink cylinder 19 takes place in such a way that the inking rollers 11, 12 and 13 rotate over the surface of the ink cylinder, moving in a direction opposite to their own, and, owing to this opposite motion of the ink cylinder as indicated by the arrow, rotate so many times over the surface of the cylinder that they are supplied with ink in finest graduation. In continuing their travel the inking rollers transmit this ink to the form 23 (Fig. 1), whereupon the actual printing of the sheet or

other work-piece is carried out by means of the platen 7.

In the proper distance from the carriage 11 a carriage 15 has been connected to the endless steel bands in such a manner that it is guided from below past the platen 7 in the direction of the arrow after the printing has been accomplished.

The carriage 15 (Fig. 2) consists of a pair of grippers pivoted at 26 to an arm 28. The latter is fixed to a shaft 29 which is rigidly connected to a lever arm 30. The latter carries adjustably a holder 31 for a guide roller 33 which cooperates with a cam 34. The cam 34 is held by a slotted bar 35 which is adjustably guided on pins and which can be secured to the press frame in adjusted position by means of a screw 37. The cam 34 carries the pin 38 which serves as stop for the arm 39. As soon as the arm 39 during the movement of the carriage in the direction indicated by the arrow touches the pin 38 it is pressed back by the latter with the result that the gripper 27 opens, as indicated by the dotted line.

The grippers 27 serve the purpose of catching the printed sheet 40, indicated by dots, while lying on the platen and to carry it off. A scale may be provided to facilitate the adjustment.

To do their work the grippers move to the lower edge of the printed sheet, open up, pass for a short distance over the surface of the platen and place themselves with their lower gripping member under the sheet. As soon as this has been done, the grippers close on the sheet and carry it over the surface of the platen upward.

These movements are caused by the roller 32 hitting the cam 34 of the contact of the arm 39 with the pins 38. During its movement around the center of the press the gripper carriage with its grippers is guided past the cam 34 in the direction of the arrow.

45 The arm 39 touches now the pin 38 and the grippers 27 open up. Simultaneously, the roller 33 meets the cam 34, the shaft 29 with the arm 28 is turned and the grippers place themselves on the surface of the platen and 50 enter under the edge of the sheet which is thus admitted between the upper and lower member of the grippers. As soon as arm 39 has been moved past pin 38, the grippers 27 close on the sheet by the pressure of a spring 55 arranged on the shaft 26 and the sheet is held securely between them. In the meantime the platen moves farther to the left away from the grippers 27 and the grippers carry the sheet upward.

60 The adjustable roller 33 with the holder 31 can be omitted. In that case the shaft 29 (Fig. 3) carries a disc 67 provided with notches 68 in its edge and engaged by a spring-pressed roller 69 or a spring-pressed 65 pawl which stop the disc after the completion

of one-eighth of a revolution. The disc is provided with studs 70 in mesh with a ratchet wheel 71 whereby the rotation of the latter is transmitted to the disc 67. Connected to the carriage 15 is the stop 72 for opening the grippers 39. The adjustable projection 73 is attached to the frame of the machine.

When the carriage 15 moves upward the wheel 71 strikes against the projection 73 at 75 and is pressed downward. This causes the wheel 71 to make a short turn which is transmitted to the studded disc 67 which catches the arm 28 whereupon the grippers 27 incline towards the surface of the platen. Arm 39 is in engagement with the stop 72, 80 is pressed by the latter and the grippers 27 open up. The lower gripper member 27 moves under the sheet and slides up. If the gripper carriage has kept on moving, the lever 39 releases the stop 72, the grippers 85 close on the sheet by a spring-pressure and carry the sheet upward.

Collapsing of the sheet is prevented by means of the long gripper rods common to all platen presses. Strong and rigid sheets can therefore easily be pushed over the surface of the platen. To prevent flimsy paper, as for instance tissue paper and the like, from collapsing, a supporting device 90 consisting of a carriage 42 has been provided above the carriage 15.

The carriage 42 consists of a pair of grippers 42 on both sides of the frame which are connected to the endless steel bands 10 and guided by the latter around the center 100 of the press.

The arms 44 are pivoted at 43 to the carriage 42 and provided with rubber tips 45. The arms 44 turn on the shafts 43 in such a manner that their rubber tips 45 are pressed against the surface of the platen and the sheet lying on top of it. The supporting arms 44 are connected to weights 46 which hold the arms in supporting position against the sheet on the platen. The weights 46 are normally prevented from pressing the arms 44 against the sheet by a spring-pressed lever 48 which is in engagement with a notch of a disc 51 secured to the upper shaft 43 and prevents the disc and the shaft 43 from turning. If the carriage 42 moves in the direction of the arrow upward, the lever 48 strikes against the pin 52, the lever 48 is moved around its bearing 53 and released from engagement with the notch in the disc 51. The disc 51 is thus released, the weights 46 move downward and turn the shafts 43 with their arms 44 far enough to allow the rubber tips 45 to press against the sheet. 110

Owing to their rough surface the rubber tips slide the sheet along by friction and carry it jointly with the grippers 27 over the surface of the platen upward. As the arms 44 should be applied to the top of the sheet at the same time as the grippers 27, 115

the stop 52 is connected to an adjustable slide and can be adjusted high or low at will.

Instead of weights springs may be used to press the supporting arms 44 against the 5 sheet.

The grippers 27 hold the sheet until it reaches the table 54 (Fig. 1) Fig. 6. To prevent the sheet from becoming bent on the way traveled by the carriage until the table 10 has been reached and to turn the printed side of the sheet upward, it is necessary to provide means for the gradual rotation of the grippers 27. This gradual rotation of 15 the ratchet wheel 55, arranged on the opposite side of the carriage, and the small toothed wheels 56 and 57 (Fig. 2) or the disc 67 with its studs 70 (Fig. 3).

The ratchet wheel 55, having eight teeth 20 or arms, is firmly connected to the cog-wheel 56 (Fig. 2) on a common shaft. Cog-wheel 56 meshes with cog-wheel 57 which firmly rests on the shaft 29. In moving the carriage 15 the ratchet wheel 55 is guided past 25 the stops 58, 59, 60 (Fig. 1). Each stop retains that tooth of the ratchet wheel 55 which is closest to the center of the press and compels the ratchet wheel to complete one-eighth of a revolution whereupon the 30 tooth can pass the stop. The cog-wheel 56 (Fig. 2) cooperates with the ratchet wheel 55 in making one-eighth of a revolution and, being in mesh with the cog-wheel 57, forces the latter to do the same. As the cog-wheel 35 57 is again firmly connected to the arm 28 by means of the shaft 29, the arm 28 together with the grippers 27 will complete one-eighth of a revolution around the shaft 29. Thus the grippers 27, before reaching 40 the table 54, are forced by four stops to make four turns, each of which is equal to one-fourth of a revolution, and take up successively the four positions, as shown by the dotted lines in Fig. 1.

45 If the grippers pass the fourth position 61, the arm 39 strikes against a stop 66 (Fig. 1) in such a manner that during further rotation the grippers open on their way and drop the sheet which slides now on the table 50 54.

The carriage is now guided along the rear side of the press. The ratchet wheel successively passes the stops 62, 63, 64 and 65, is forced by each of them to make one-eighth 55 of a revolution and thus completes a full turn. With the wheel the grippers 27 revolve once about the shaft 26 and after passing the stop 65 return to their initial position.

60 Exactly the same process takes place, if the arrangement as shown in Fig. 3 is employed, where instead of the cog-wheels 56, 57 the ratchet wheel 71 together with the studded disc 67 is operative.

65 The carriage 42 moving in advance of the

carriage 15 (Figs. 2 and 4) gradually occupies during its travel around the upper disc 3 a reversed position. The shafts 43 which during the upward movement of the carriage are directed upward occupy after their 70 rotation around the disc 3 a downward position. By this reversal of the former positions the weights 46 act in opposite direction and the disc 51 which was moved by means of the weights in the direction towards the platen is now moved back into the opposite direction. The notch in the disc 51 returns thus to its position under the tooth of the lever 48, the tooth snaps into the notch and the device is locked again. In this locked 80 position it passes around the other half of the center part of the press and returns to its original position.

If the ink distributing cylinder 19 is arranged in the upper part of the platen press, as shown in Fig. 4, it is necessary to place the table 54 above the press, because the ink cylinder 19 occupies the upper part of the press and the sheet can not be delivered directly by the carriage 15 to the table 54 but 85 is taken off the carriage by means of the arms 76, arranged on both sides, and the grippers 87 and carried to the table 54.

The arms 76 Fig. 4 are driven through the medium of the main crank in connection 90 with the rod 79, the linked-on rack 78 and the wheel sector 80 firmly connected to the arm 76. By these intermediary means the arms 76 are rocked by the rod 78 and moved either upward or downward over the table 95 100 105 110 115 120 125 130 135 140 145 150 155 160 165 170 175 180 185 190 195 9960 9965 9970 9975 9980 9985 9990 9995 10000 10005 10010 10015 10020 10025 10030 10035 10040 10045 10050 10055 10060 10065 10070 10075 10080 10085 10090 10095 10100 10105 10110 10115 10120 10125 10

slide with their open jaws over the edge of the sheet, catch it by closing the jaws and pull it out of the grippers 27. The carriage 15 continues to move, the arms 76 move back, 5 take the sheet along by means of their grippers 87 and carry it to the table 54. After reaching their final position the grippers 87 open through the action of a stop and drop the sheet on the table 54.

10 The delivery device may be removed for carrying out certain kinds of work so that the inking rollers are operated alone together with the cylinder inking arrangement in such a manner that the above-described cylinder inking arrangement 12, 13, 15 14 forms with the cylinder 19 which moves in an opposite direction from that of the inking rollers a printing press without delivery device. In the latter case the cylinder 19 together with the distributing rollers 21 may be arranged in the lower part of the press (Fig. 6) or in the upper part of the press (Fig. 4).

Cylinder inking as shown in the press in Fig. 1 can also be replaced by table inking so that the gripper device cooperates with the table inking. In that case the cylinder 9 is replaced by a semi-circular inking table which serves for the purpose of ink distribution. In addition a straight inking table may be arranged at the rear of the machine.

If the press is to run at a high speed, an arrangement is advisable which causes a slow movement of the inking rollers, 12, 13, 14 and the delivery device 15, 42 at a high speed of the platen; the slower the former move, the better is their work.

This arrangement consists in providing 40 two roller carriages each and two sets of delivery devices for the endless band 10. For this purpose the spur wheel 4 is made twice as large as shown in the press in Fig. 1. The effect of this change is that at each to- 45 and-fro movement of the platen the band 10 is conveyed only one-half of its length. The two roller carriages and two sets of delivery devices attached to it thus become operative alternately at each printing action of 50 the platen and run therefore at half speed.

Having now particularly described and ascertained the nature of my invention and in what manner the same is to be performed, I declare what I claim and desire to secure 55 by Letters Patent is:—

I claim:—

1. In a platen press the combination of a cylinder inking arrangement, a platen, endless bands adapted to rotate around the center of the press, and a number of inking rollers secured to the said bands by means of carriages in order to rotate around the center of the press so that the inking rollers during their travel rotate on the surface of 60 the ink cylinder, and furthermore, of rollers 65 the ink cylinder, and furthermore, of rollers

adapted to supply the ink cylinder with ink, a table, and means of taking the printed sheets off the platen and deliver them to a receiving table, while the inking rollers are led around the center of the press and 70 guided, for the purpose of receiving ink, over the ink cylinder rotating in the opposite direction to that of the inking rollers in order to cause thereby a quicker rotation of the inking rollers on the ink cylinder, sub- 75 stantially as described.

2. In a platen press the combination of a cylinder inking arrangement, a platen, endless bands adapted to rotate around the center of the press, and a number of inking 80 rollers secured to the said bands by means of carriages in order to rotate around the center of the press so that the inking rollers during their travel rotate on the surface of the ink cylinder, and furthermore of rollers 85 adapted to supply the ink cylinder with ink, while a gripping device on a carriage is connected to the endless band a distance in advance of the inking rollers and their carriage and adapted to grip the sheet on the 90 platen and deliver it to a receiving table, substantially as described.

3. In a platen press the combination of a cylinder inking arrangement, a platen, endless bands adapted to rotate around the center of the press, and a number of inking 95 rollers secured to the said bands by means of carriages in order to rotate around the center of the press so that the inking rollers during their travel rotate on the surface 100 of the ink cylinder and furthermore of rollers adapted to supply the ink cylinder with ink, and a gripping device connected by means of a pivoted holder to a carriage which is fastened to the endless band and 105 cooperates with adjustable cams and stops in such a manner that the grippers follow the movement of the platen, are opened, catch the sheet, close on it and finally deliver the sheet, to a receiving table, substantially as 110 described.

4. In a platen press the combination of a cylinder inking arrangement, a platen, endless bands adapted to rotate around the center of the press, and a number of inking 115 rollers secured to the said bands by means of carriages in order to rotate around the center of the press so that the inking rollers during their travel rotate on the surface of the ink cylinder, and furthermore of rollers 120 adapted to supply the ink cylinder with ink, and of a wheel which is pivoted to the gripper carriage and cooperates with stops so as to turn it by steps for the purpose of turning the sheet, while the grippers, by means of cog-wheel transmission, are also turned and finally opened by means of stops which causes them to drop the sheet on a receiving 125 table, and the arrangement that the wheel during its continued movement is turned by 130

suitable stops in such a manner that the grippers return to their initial position, substantially as described.

5. In a platen press the combination of a cylinder inking arrangement, a platen, endless bands adapted to rotate around the center of the press, and a number of inking rollers secured to the said means of conveyance by means of carriages in order to 10 rotate around the center of the press so that the inking rollers during their travel rotate on the surface of the ink cylinder, and furthermore of rollers adapted to supply the ink cylinder with ink, grippers connected by means of a pivoted holder to a carriage which is fastened to the endless band, and weight-operated rubber-tipped arms 15

connected by means of a carriage to the endless band in advance of the grippers so that they can be applied to the upper part of the 20 sheet while the grippers catch the latter which is then guided off the platen by the arms, and delivered to a receiving table, the arms being led to the sheet by means of weights and actuated by means of a lever 25 and adjustable stops, substantially as described.

In testimony whereof I affix my signature in presence of two witnesses.

EDUARD GROSSE.
